UNITED STATES PATENT OFFICE

117,433

DESIGN FOR COMBINED FLARES, AND RECEPTACLE THEREFOR

Oliver C. Ritz-Woller, Chicago, Ill.

Application August 14, 1939, Serial No. 86,659

Term of patent 7 years

To all whom it may concern:

Be it known that I, Oliver C. Ritz-Woller, a citizen of the United States residing at Chicago, in the county of Cook and State of Illinois, have invented a new, original, and ornamental Design for Combined Flares and Receptacle Therefor, of which the following is a specification, reference being had to the accompanying drawing, forming part thereof.

In the drawing,

Fig. 1 is a front elevational view of combined flares and receptacle therefor embodying my new design;

Fig. 2 is a side elevational view thereof looking toward the left side of Fig. 1;

Fig. 3 is a side elevational view thereof looking toward the right side of Fig. 1;

Fig. 4 is a top plan view thereof; and

Fig. 5 is a sectional view thereof taken on the line 5—5 of Fig. 1.

I claim:

The ornamental design for combined flares and receptacle therefor, substantially as shown.

OLIVER C. RITZ-WOLLER.
